UNITED STATES PATENT OFFICE

162,515

CAN CARRYING DEVICE

Keith W. Burge, Highland Park, Ill.

Application March 25, 1950, Serial No. 8,779

Term of patent 14 years

(Cl. D58—5)

To all whom it may concern:

Be it known that I, Keith W. Burge, a citizen of the United States, residing in the county of Lake, Highland Park, Illinois, have invented a new, original, and ornamental Design for a Can Carrying Device, of which the following is a specification, reference being had to the accompanying drawing, forming part thereof.

Figure 1 is a plan view of a can carrying device, showing my new design;

Figure 2 is a front elevational view, partly broken away, of the device;

Figure 3 is an end view of the device; and

Figure 4 is a perspective view, partly broken away, of the carrying device.

The dotted lines in the drawing represent cans

or containers and are for illustrative purposes only.

I claim:

The ornamental design for a can carrying device, as shown and described.

KEITH W. BURGE.
